UNITED STATES PATENT OFFICE.

EDWARD BOEKENKAMP, OF ST. LOUIS, MISSOURI, ASSIGNOR TO AMERICAN STOVE COMPANY, OF ST. LOUIS, MISSOURI, A CORPORATION OF NEW JERSEY.

BURNER.

Application filed December 15, 1927. Serial No. 240,190.

This invention relates to improvements in gasoline burners, and the primary object is to provide a lighter for starting the burner that is so constructed that the heat from a 5 match is sufficient for starting it, after which the lighter will continue to burn until the main generator is sufficiently heated for supplying gasoline vapor for the main burner.

A further object of the invention is to provide an especially constructed mixing tube 10 for the vapor from the lighter generator so that the mixing tube, after the same is started by the heat of a match, will provide heat for the lighter generator and also for the main 15 generator until the latter is sufficiently heated to supply gasoline vapor for the main burner.

Other further objects, novel features of construction and improved results of the invention will appear from the following description and accompanying drawings.

In the drawings:

Figure 1 is a top plan view of the burner embodying the present invention.

Figure 2 is a vertical sectional view of the burner, the generator and gasoline feed pipes being shown in full lines.

Figure 3 is a bottom view of the burner.

Figure 4 is an enlarged detail perspective 30 view of the match lighter generating tube and the gasoline feed connection to the match lighter and the main generator.

I am aware that it is not novel to provide a gasoline burner with the main generator 35 to supply gasoline vapor to a main burner and to provide an initial heating device for the said generator. The present invention pertains to a special construction of the lighter generator and its mixing tube adapted 40 to operate in the manner hereinafter described.

Referring now to the drawings, in which a preferred embodiment of the invention is 45 illustrated, A designates a burner, B the main generator, C the match lighter generating tube, D the copper plate mounted upon the match lighter generating tube, E the mixing tube of the lighter, and F the main gasoline supply pipe or conduit.

50 Referring to the drawings in more detail and describing the invention more specifi-

cally, it will be seen that the burner A is provided with a burner cap 5 having thereon a plurality of raised burner orifices 6. This burner cap is surmounted upon and closes 55 the burner chamber 7 through which chamber extends a raised housing 8 beneath which extends the main generator B. The extreme inner end 9 of the generator, which is in reality a nozzle, is in communication with the 60 end 10 of the conduit 11 which conduit in turn communicates with a second conduit 12, one end 13 of which is in communication with the burner chamber 7 and conveys thereto the gas from the main generator for the burner A. 65

Although only one burner is illustrated in the drawings it will be readily realized that other burners can be operated from the single generator B by attaching them to the opposite end of the conduit 12.

The passageway 8 is in communication with the burner chamber 7 by reason of the plurality of slots or orifices 14 which are placed in the top of the passageway.

Intermediate its length the passageway 8 75 is provided with an opening 15 having a circumferential flange or collar 16. The burner cap 5 is provided centrally with an opening 17 positioned to register with the opening 15 of the passageway while the under side of the burner cap is provided with a downwardly extending circumferential flange 18 around the central opening 17 and this flange abuts the flange 16. The flange 18 is offset from the edge of the opening 17 so that when the burner cap is in place it rests directly upon the upper end of the flange 16 as appears at 19.

The lighter mixing tube which is designated by E, is attached to the bottom of the burner chamber 7 by a suitable bracket 20 and 80 bolts 21. One end of this mixing tube E is of an open bell shape as appears at 22. A portion 23 of the mixing tube parallels the bottom of the burner immediately below the main generating tube B while the opposite 85 end 24 of the mixing tube extends outwardly and downwardly beyond the burner bottom. A shield 25 attached to the mixing tube E by screw 26 or the like entirely surrounds the outwardly extending end 24 thereof. The 90 shield has an open bottom 27.

The bottom of the outwardly extending

end 24 of the mixing tube is provided with a plurality of slots or orifices 28.

The lighter generating tube C is supported from the main generating tube B through the instrumentality of the gasoline delivery pipe 29, which pipe delivers gasoline into the pipe or fitting 30. The lighter generating tube is made of steel and extends from the fitting 30 inwardly beneath the bottom of the end 29 of the mixing tube E, the inner end 31 of the tube being in front of and slightly separated from the open end 22 of the mixing tube. The inner end 31 of the tube passes through a suitable opening 32 in a shield 33 which is attached to the mixing tube E as at 34. This shield 33 is so shaped as to partially close the open inner end of the shield 25 as clearly appears in Figure 2 of the drawings.

Attached to the lighter generating tube C by any suitable means is a copper plate D, which plate is positioned to be immediately below the orifices 28 in the lower face of the outwardly extending end 24 of the mixing tube E and also incidentally below the open lower end of the shield 25.

The generator tube carries a valve 25 which is controlled through the wing nut 36.

The admission of gasoline to the main generator tube B through the main conduit F is constant but the main generator tube is provided with a valve stem 37 the inner end 38 of which closes the orifices in the nozzle 9. This valve is operated through a suitable knob 39.

It has been previously pointed out that a portion 23 of the mixing tube E parallels the bottom of the burner chamber beneath the main generating tube. This portion of the mixing tube is provided with outlet burner orifices 41.

Attention is directed to the fact that the copper plate D is provided with a plurality of holes 40.

Operation.

Considering the burner illustrated in the drawings with the valves in the positions illustrated, in operating the burner a match is held under the copper plate D attached to the lighter generating tube C. This match is held beneath the plate and tube for approximately fifteen seconds and heats both of these members.

The wing nut 36 is then rotated to open the generating tube valve 35 which allows the gas which has been generated in the tube by reason of the heat from the match to enter the open bell shaped end 22 of the lighter mixing tube E. This gas burns through the burner orifices 41 in the mixing tube beneath the main generator tube B and heats the main generator tube. A portion of the gas in the mixing tube E also escapes from the orifices 28 in the end 24 of the tube and burns downwardly against the copper plate which is attached to

the lighter generator tube C and keeps this tube hot as long as it is necessary to keep the lighter in operation.

After about one minute's operation of this lighter the main generating tube B has been heated sufficiently to generate gas for the operation of the main burner. The valve 38 of the main generator B is then opened by rotating the knob 39 and the gas in the generator escapes through the nozzle 9 into the end 10 of the conduit 11. The passage through the end 10 of the gas takes with it a certain amount of air through the opening 42 in the end 10 of this conduit. The gas in the conduit 11 is of course fed to the burner chamber 7 and also to the burner chambers of any other burners by the conduit 12.

The gas upon entering the burner chamber 7 passes upwardly through the burner cap orifices 6 where it can be ignited for the operation of the main burner.

There is also what might be termed a sub-fire in the main burner chamber. The gas in this chamber also burns downwardly through the orifices 14 against the main generator tube B to keep this tube constantly hot for the generation of gas so long as the main burner is in operation.

After the main burner is in operation the operation of the lighter is discontinued by closing the valve 35.

Lighter.

Attention is particularly directed to the fact that the lighter generating tube is made of steel rather than of brass, copper, or non-ferrous metal. It has been found through experimentation that a steel tube is better in use for the reason that the steel tube withstands the operating temperature better than do brass, copper or non-ferrous metal tubes. I have also additionally discovered that a steel tube is not as subject to the action of sulphur and other impurities in the gasoline as is the case with the tube made of softer metal.

Experimentation has further shown that the carbon which is necessarily formed in a burner of this tube does not adhere to the steel tube as readily as it does to one made of non-ferrous metal. The lessening of the carbon deposits is of course a material advantage.

It is thought that it will be readily apparent that the purpose of the copper plate D is to absorb heat from the match and conduct it to the tube C so that the two will reach the necessary starting temperature very quickly.

The only valves in the devices are those for the lighter and in the main generator. Gasoline will be at all times present in both the main generator tube and the lighter generator tube. With the construction which has been described it will be seen that

the lighter and the main generator are built as one unit so that a single gasoline feed pipe delivers the gasoline to both. A single delivery pipe for both the main generator and the lighter generator has a decided advantage from a manufacturing stand-point.

Having thus described my invention, what I claim and desire to secure by Letters Patent is:

1. In combination with a hydrocarbon burner having main and a sub-fire burner, a main generator positioned to receive heat from said sub-fire burner, a lighter and supplemental generator having a generating tube carrying a copper plate, and a mixing chamber for said supplemental generator having therein a burner for heating the main generator and a sub-fire for heating the copper plate of the supplemental generator.

2. A hydrocarbon burner comprising a main burner, a main generator therefor, a lighter generator below the main generator, a lighter mixing tube under and adjacent said main burner, a lighter generator having communication with said mixing tube, said mixing tube having an extension above and adjacent the lighter generator, said extension provided with downwardly extending burner openings adapted to heat the said lighter generator after it has been initially started, the parts combined for the purpose specified.

3. A hydrocarbon burner comprising a main burner, a generator for the said main burner located vertically under said burner, said main burner having in its lower wall burner openings for heating the main generator, a lighter mixing tube located vertically under the main burner and main generator and provided with an open lower end, a lighter generator having communication with the lower open end of said lighter mixing tube, said mixing tube having an extension adjacent and above the lighter generator, said extension having downwardly extending burner openings for heating the said lighter generator after starting the same, the parts combined for the purpose described.

4. A hydrocarbon burner comprising a main burner, a main generator for said burner located below it, a lighter mixing tube located below said generator and having an open lower end, a lighter generator communicating with said open end, the said lighter mixing tube provided with an extension above and beyond said open end and adjacent the said lighter generator, said extension provided with downwardly extending burner openings for heating the lighter generator, said lighter mixing tube also having its upper main wall provided with burner openings for initially heating the main generator, the parts operating as described.

5. A hydrocarbon burner comprising a main burner, a main generator located below the said main burner, a lighter mixing tube located below the said generator, said lighter mixing tube having an open end, a lighter generator communicating with said open end, the lighter mixing tube provided with an extension extending beyond said open end and provided with burner openings for heating the said lighter generator, said lighter mixing tube adapted to heat the main generator, and the lighter generator provided with a member adapted to accumulate heat from a match sufficient for starting said lighter generator after which it is heated by the burner openings of said mixing tube extension, the parts operating for the purpose specified.

6. A hydrocarbon burner comprising a main burner and a main generator below the said burner, a lighter mixing tube below the said main generator having an open lower end, a lighter generator communicating with the lighter mixing tube, said mixing tube having burner openings above the lighter generator for heating the lighter generator and provided also with burner openings located in its upper portion for heating the said main generator, for the purpose specified.

7. A hydrocarbon burner provided with a main burner and a main generator below and adjacent thereto and normally heated by the main burner, a lighter mixing tube under and adjacent the said main generator and main burner, and having an open lower end, a lighter generator communicating with the open lower end of the lighter mixing tube, the lighter mixing tube having an extension above said lighter generator which is provided with downwardly extending burner openings to cause its flame to impinge against the said lighter generator, the said lighter mixing tube having upwardly extending burner openings in the upper main portion thereof for heating the main generator, the parts operating as described.

8. The combination in a hydrocarbon burner having main and sub-fire burners, a main generator extending to a position to be heated by the said sub-fire, a combined match lighter and supplemental generator tube carrying a copper plate, an initial mixing tube having in its upper portion burner openings adapted in starting to heat the said main generator, the mixing tube having therein downwardly extending openings adapted to impinge on the said lighter generator and the said copper plate of the lighter generator, the parts adapted to operate as described.

9. A hydrocarbon burner comprising a main burner having burner openings in its top and downwardly extending burner openings in its bottom portion, a generator located below the said main burner and adapt-

ed to be heated by the burner openings in its bottom, a lighter mixing tube located under the generator with its lower end open, a lighter generator communicating with the said open end of the mixing tube, the mixing tube having a portion extending over the lighter generator that is provided with downwardly

extending openings for heating the said generator, valves for the main generator and the lighter generator, the parts combined for the purpose specified. 10

In testimony whereof I hereunto affix my signature.

EDWARD BOEKENKAMP.
